DESIGN.

—o—
N. KOMORI.

CARPET.

No. 17,732.

Patented Sept. 20, 1887.

UNITED STATES PATENT OFFICE.

NORIC KOMORI, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,732, dated September 20, 1887.

Application filed August 16, 1887. Serial No. 247,121. Term of patent 3½ years.

To all whom it may concern:

Be it known that I, NORIC KOMORI, of New York city, in the county and State of New York, have invented a new and original Design 5 for Carpets, of which the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

My design is composed of a body part, A, and a border, B.

The characteristic feature of the body A lies 20 in the broad expanded palm-like leaves, that are gathered into groups, irregularly disposed over the face of the carpet. These leaves are of a rich tropical form, and they spread out from the center of each group, so as to form a loose irregular cluster. Portions of stem-work 25 appear in the intervals between these groups, bearing other smaller leaves and here and there a large and prominent circular flower. Depending from other parts of the stem are smaller bell-shaped flower forms. Running

over the face of each of the groups of large leaves is a slender stem-work bearing small 30 inconspicuous flower forms. Some star-shaped flowers appear in the spaces between the large groups.

My border B has an inner ornamented margin. The middle portion shows similar large 35 palm-like leaves grouped together. Between the groups is a stem-work bearing large circular flowers and smaller leaves. A slender stem-work extends over the face of the larger leaves bearing similar inconspicuous flower 40 forms. Here and there are a few star-shaped flowers. My border has an outer margin or band ornamented with conventional leaf groups or forms.

What I claim as new, and desire to secure 45 by Letters Patent, is—

1. In a design for carpets, the body A, substantially as shown.

2. In a design for carpets, the border B, substantially as shown.

3. The design for carpets, consisting of the body A and border B, substantially as shown.

NORIC KOMORI.
